CRUSHING MACHINE

Oscar C. Gruender, Milwaukee, Wis., assignor to
Nordberg Manufacturing Co., Milwaukee, Wis.,
a corporation of Wisconsin

Application June 10, 1935, Serial No. 25,823

2 Claims. (Cl. 83—10)

This invention relates to gyratory crushers and is particularly applicable to gyratory or cone crushers made in general accordance with the disclosure of Patent 1,537,564, and operating according to the process claimed in Patent 1,537,565, both granted to Edgar B. Symons on May 12, 1925. It is not limited, however, to use with such structure or method as it may be employed with crushers differing in form and in mode of operation, such as the so-called old line gyratory crushers. One purpose of the invention is to compensate for wear at the upper portion of the bowl liner and mantle of a crusher. Another object is the provision of means for preventing material nipped between the liner and mantle from being thrown or pinched outwardly. Another object is the provision of means for preventing any head of feed above the crushing cavity from penetrating into the crushing cavity at such a rate or in such volume as to interfere with the desired crushing operation. Another object is the provision of an opposed bowl liner and mantle in which the upper or inlet end of the crushing cavity defined thereby is so shaped that the angle between the opposed parts is reduced to within the angle of nip.

Other objects will appear from time to time in the course of the specification and claims.

I illustrate my invention more or less diagrammatically in the accompanying drawing, where-

in—

Figure 1 is a vertical axial section through a crusher having a bowl liner and a mantle in position, made in accordance with my invention; and

Figure 2 is an axial section through one side of the crushing cavity, illustrating the bowl liner and mantle in section and to a somewhat enlarged scale as compared to the scale of Figure 1; and

Figure 3 is a similar section through a modification.

Like parts are indicated by like symbols throughout the specification and drawing.

Referring to the drawing, 1 indicates a portion of the base frame of the device, the details of the frame being not of themselves part of the present invention. 2 represents a portion of an eccentric which is provided with an inner bushing 3, conforming to the downwardly tapered shaft 4. It will be understood that any suitable means may be employed for causing rotation of the eccentrically apertured sleeve 2 whereby the shaft 4, which seats in the eccentric aperture has imparted to it a gyratory movement. The shaft 4 carries near its upper end a generally conic head 5 which is provided with a lower spherical bear-

ing surface 6 which co-acts with a babbitted or suitably anti-frictional bearing 7 which may be supported on any suitable support or casting 8 which is supported on the base frame 1 of the machine.

Suitable guards 9 and 10 serve to prevent the escape of oil and the exclusion of dust, and co-operate with the outer skirt 11 for this purpose. 12 indicates any suitable oil sump.

20 is a conical mantle mounted on the crushing head or cone 5. This mantle includes a generally conic inner surface 21 and a generally conic outer surface 22. At the upper edge of the outer surface 22 there is provided an enlargement or expansion 23 of the mantle which terminates in the concave conic upper edge surface 24. Any suitable means may be employed for holding the mantle 20 in position, for example, a nut 25 and any suitable means for forcing said nut downwardly against the conic surface 24, to which the lower surface 26 of the nut conforms. 28 is any suitable feed limiting plate or member positioned upon the upper end of the shaft 4.

30 indicates a spider having an inwardly conic surface 31 which conforms generally to the outer conic surface 33 of the mantle or bowl liner 32. It will be understood that the spider 30 is mounted in any suitable fashion upon the base 1, preferably with a yielding release. Inasmuch as these features of the device do not of themselves form any part of the present invention they are not illustrated herein. It will be understood, however, that the present liner and mantle are applicable, for example, to a structure such as is shown in Edgar B. Symons Patent 1,920,488, issued on August 1, 1933. The bowl liner 32 is shown herein as with a generally conic inner surface 34 opposed to and upwardly diverging outwardly from the outer surface 22 of the mantle 20.

It is provided, however, with an upper enlargement or inward extension generally indicated as 35 which extends to and joins with the upper conic end surface or edge 36. The mantle 32 may be held in place upon the conic spider as for example by the hook shaped lugs 37 which may receive U-bolts 38 or any other suitable securing structure.

40 indicates any suitable feeding or confining hopper herein shown as mounted upon the conic spider 30.

In observing the cross-section of the crushing cavity defined by the opposed mantle 20 and the bowl liner 32 it will be seen that the main portion of the crushing cavity is defined by opposed walls 22 and 34 which flare or deflect away from each

other from bottom to top of the crushing cavity. The addition, however, of the opposed enlargements 23 and 35 causes a decrease in the distance separating the opposed crushing surfaces, at the 5 upper portion or neck of the crushing cavity. One result of this decrease, taken in connection with the contour of the opposed parts is a reduction of the angle between the opposed parts to well less than the angle of nip. In other words, 10 a stone gripped between the opposed portions of the members 23 and 35 will not be pinched or thrown upwardly out of the cavity, but will actually be crushed where the upper opening of the crushing cavity is widely flared. The angle of 15 the opposed crushing surfaces may become such that a boulder, particularly a rounded stone of hard material, will not be crushed, but will be nipped or pinched and thrown upwardly out of the crushing cavity. Sometimes hard rounded 20 rocks, colloquially called "nigger heads" may be pinched out of the crushing cavity and thrown into the air at great velocity, causing actual danger to the men working about the machine. This pinching of rocks interferes with the normal 25 crushing and increases the wear on the opposed crushing parts. If the rock fragments are caused to slide across the surfaces of the opposed crushing members, the result is a scratching abrasive wearing action which is much more marked and 30 damaging than the wear upon the opposed faces when the rock is actually compressed and breaks. It is as if the material being crushed were actually planing across the wearing surfaces and this abrasive action is the prime reason for the heavy 35 wear caused when the material can be nipped out through the upper opening of the crushing cavity. Once the material near the upper edge of the ordinary flared top bowl liner wears away, the angle between the opposed liner and mantle im- 40 mediately becomes wider, and the chance for material to slip or be wedged back toward the feed or entrance end becomes aggravated and wear is increased and crushing efficiency is diminished.

45 The above described mantle 20 and liner 32 have their upper ends or edges so shaped that the angle between the opposed parts 23 and 35 is reduced well within the angle of nip. Furthermore, as a supplemental advantage, the very thickening 50 of the metal at the top of the liner and mantle increases the period during which the opposed crushing members can be used, as it increases the time which elapses before the upper edges of the two wearing parts are so worn down that replace- 55 ment is necessary.

The dotted lines in Figure 2 indicate more or less diagrammatically the direction of wear. The dotted line *a* indicates the form of a worn liner where the portion 35 is omitted. The line *b* 60 indicates the wear of a liner of the shape shown in Figure 2 in which the portion 35 is employed.

In other words, there is a great reduction in waste and in length of wearing time, in addition to an improvement in crushing effort.

Prevailing, applicant controls his feed by employment of the above described feed plate 28 but under some circumstances the hopper 40 may be filled with material. In such case, the relatively close approach of the members 23 and 35 serves as a supplemental feed limiting means of value, which prevents a choking of the larger cavity below. 10

It will be realized that whereas I have described and shown a practical and operative device, nevertheless many changes might be made in the size, shape, number and disposition of parts without departing from the spirit of my invention. I therefore wish my description and drawing to be taken as in a broad sense illustrative and diagrammatic rather than as limiting me to my specific showing. 15

I claim:

1. In combination, a bowl liner and a mantle for a gyratory crusher, the liner and mantle both being generally conic and having opposed generally conical surfaces, the liner overhanging the mantle, the liner and mantle being provided adjacent their upper edges with opposed thickened portions of convex curvilinear axial cross section, said opposed portions defining an angle of nip adapted to prevent upward escape of particles nipped therebetween, said liner and mantle and the thickened portions defining a cavity which increases substantially in diametrical thickness from the bottom upwardly toward an intermediate zone of maximum separation, and from the top downwardly toward the same intermediate zone, the top of the crushing zone being thereby provided with a zone of restriction adapted to prevent unintended upward movement of the particles from said zone of maximum separation. 23

2. In combination, a bowl liner and a mantle for a gyratory crusher, the liner and mantle both being generally conic and having opposed generally conical surfaces, the liner overhanging the mantle, the liner and mantle being provided adjacent their upper edges with opposed thickened portions of curvilinear axial cross section, said opposed portions defining an angle of nip adapted to prevent upward escape of particles nipped therebetween, said liner and mantle and the thickened portions defining a cavity which increases substantially in diametrical thickness 30

from the bottom upwardly toward an intermediate zone of maximum separation, and from the top downwardly toward the same intermediate zone, the top of the crushing zone being thereby provided with a zone of restriction adapted to prevent unintended upward movement of the particles from said zone of maximum separation. 35

3. In combination, a bowl liner and a mantle for a gyratory crusher, the liner and mantle both being generally conic and having opposed generally conical surfaces, the liner overhanging the mantle, the liner and mantle being provided adjacent their upper edges with opposed thickened portions of curvilinear axial cross section, said opposed portions defining an angle of nip adapted to prevent upward escape of particles nipped therebetween, said liner and mantle and the thickened portions defining a cavity which increases substantially in diametrical thickness 40

from the bottom upwardly toward an intermediate zone of maximum separation, and from the top downwardly toward the same intermediate zone, the top of the crushing zone being thereby provided with a zone of restriction adapted to prevent unintended upward movement of the particles from said zone of maximum separation. 45

4. In combination, a bowl liner and a mantle for a gyratory crusher, the liner and mantle both being generally conic and having opposed generally conical surfaces, the liner overhanging the mantle, the liner and mantle being provided adjacent their upper edges with opposed thickened portions of curvilinear axial cross section, said opposed portions defining an angle of nip adapted to prevent upward escape of particles nipped therebetween, said liner and mantle and the thickened portions defining a cavity which increases substantially in diametrical thickness 50

from the bottom upwardly toward an intermediate zone of maximum separation, and from the top downwardly toward the same intermediate zone, the top of the crushing zone being thereby provided with a zone of restriction adapted to prevent unintended upward movement of the particles from said zone of maximum separation. 55

5. In combination, a bowl liner and a mantle for a gyratory crusher, the liner and mantle both being generally conic and having opposed generally conical surfaces, the liner overhanging the mantle, the liner and mantle being provided adjacent their upper edges with opposed thickened portions of curvilinear axial cross section, said opposed portions defining an angle of nip adapted to prevent upward escape of particles nipped therebetween, said liner and mantle and the thickened portions defining a cavity which increases substantially in diametrical thickness 60

OSCAR C. GRUENDER.
